UNITED STATES PATENT OFFICE.

JOHN S. GULLBORG, OF CHICAGO, ILLINOIS, ASSIGNEE TO ALEMITE DIE-CASTING & MFG. CO., OF CHICAGO, ILLINOIS, A CORPORATION OF ILLINOIS.

DIE-CASTING MACHINE.

1,322,502.

Specification of Letters Patent. Patented Nov. 18, 1919.

Application filed May 24, 1918. Serial No. 236,283.

To all whom it may concern:

Be it known that I, JOHN S. GULLBORG, a citizen of the United States, residing at Chicago, in the county of Cook and State 5 of Illinois, have invented a certain new and useful Improvement in Die-Casting Machines, of which the following is a full, clear, concise, and exact description, reference being had to the accompanying drawings, forming part of this specification.

My invention relates to the art of die casting and has special reference to improvements in die casting machines and processes.

Generally, the object of my invention is to provide an improved automatic die casting machine.

More specifically my object is to improve certain details of operation, simplifying 20 some thereof, making others more certain and positive in their operation or results, and making operations automatic which have heretofore been manual. A further object of my invention is to insure a higher 25 percentage of more nearly perfect castings, to simplify the closure of the pot and nozzle, to automatically remove or cut off the sprue and to provide simplified automatically operated mechanism to effect these 30 and other functions.

My invention resides in the herein described die casting machine, said machine embodying my invention in a form which I have so far found best adapted to attain 35 the above mentioned objects, and by means of which I am enabled to attain still other objects as will appear hereinafter.

My invention also consists in the arrangement and combinations of devices and parts 40 and in the various features of construction and operation as described herein and particularly pointed out in the appended claims.

In the drawings:

Figure 1 is a front elevation of my improved machine, the shield and other parts being broken away to best disclose the invention;

Fig. 2 is a rear elevation of the machine 50 certain parts being broken away for illustrative purposes;

Fig. 3 is a vertical longitudinal sectional view of the machine viewed from the same side as Fig. 1;

Fig. 4 is a plan view of the machine, the

lower part of the shield being shown in section and part of the operating mechanism being shown in section on line 4-4 of Fig. 3;

Fig. 5 is a fragmentary horizontal section taken substantially on the line 5-5 of Fig. 3 and particularly illustrating the means for adjusting the pressure of the pot nozzle against the die;

Fig. 6 is an end elevation of the machine 65 looking from the left hand end Fig. 1, the shield being removed and parts of the frame broken away to best disclose the operation of the machine;

Fig. 7 is an enlarged fragmentary side 70 elevation of a portion of the machine taken partly in section on the line 7-7 of Fig. 4 and particularly illustrating the mechanism for cutting off the sprue;

Fig. 8 is a view similar to Fig. 7 showing 75 the sprue cutting parts in their final position;

Fig. 9 is enlarged fragmentary transverse sectional view of the machine on the line 9-9 of Fig. 7;

Fig. 10 is a fragmentary plan sectional view particularly disclosing the cams and mechanism for the laterally movable die members;

Fig. 11 is a fragmentary detail section 85 on the line 11-11 of Fig. 10; and

Fig. 12 is a fragmentary detail vertical section on the line 12-12 of Fig. 10.

Die casting machines of this kind have a die mold in which the articles to be produced are cast from molten metal.

The mold consists of two or more sections or parts which are adapted to be separated to remove the castings and to be closed to receive the molten metal.

The metal is maintained in molten condition in a pot which is arranged for connection to the mold at the proper instant, and the molten metal is forced, under high pressure, into the mold. My machine is arranged to hold the parts of the die in closed relation by pressure and as the pressure under which the metal is forced into the mold is relatively high, being about 500 lbs. per square inch, the machine and its parts must 100 be proportionately strong to properly withstand such pressure. To prevent accidents to the workmen, during the casting operation, a sheet metal shield is provided which effectively covers the machine at this time 110

and prevents molten metal doing any damage or reaching the workmen even should the die not be closed at the time the metal is forced into the mold. As a further 5 caution there are automatic means provided to prevent the application of the pressure to force the metal into the mold unless the shield has reached its protecting position.

After the mold has been filled and the 10 cast made the mold is separated, and the dies are formed so that as they are separated the casting is first stripped out of one of the die members and as the dies continue to open the casting is stripped or forced out 15 of the other die member.

15 I have found that it makes the castings cleaner if the sprue is cut off of the casting before the mold is opened and I am enabled to accomplish this by means of my 20 present invention.

20 Such machines to be economical and properly effect the result of cutting down manufacturing costs, must necessarily produce the castings at a rapid rate, and as there 25 are quite a large number of steps or operations which must occur in proper sequence, the time allowance for each step is necessarily very limited, and each must occur in a minimum of time.

30 I have found that I can greatly decrease the percentage of poor or non-perfect castings by first stripping one part of the mold from the casting and stripping the casting from the other part of the mold by a relative movement, which, though it occupies as a whole but a very short interval of time, yet during the actual stripping action and at the instant of breaking the contact between the parts the movement is relatively slow. This avoids the effect of a 35 hammer-like blow and in consequence largely avoids breakages which have heretofore prevailed to a greater or less extent.

40 At the close of one complete cycle of operations necessary to produce one casting, it 45 is essential that the several parts of the machine be inspected and cleaned before starting upon the next cycle. I therefore provide a very simple and positive, one cycle 50 stop mechanism, which makes it necessary for the operator to manually start the machine into operation for each casting and thus positively avoiding accidents which 55 might occur should the operation not be manually controlled. This feature is shown in a prior application filed by me.

The various functions or operations of the several parts of the machine are properly timed and effected by a system of suitable cams and cam drums and the starting of the cycle of operation is controlled by a hand lever conveniently placed for the operator. In the following description of the machine, its parts, relations, functions and 65 operations, the many advantages which re-

sult from my invention will become apparent.

As illustrated in said drawings, the frame 1 of my machine comprises a base or die plate or table 2 upon which the dies and their operating mechanism are arranged, and a depressed portion 3 at one end of the base plate for accommodating the metal pot and its connections, the plate being supported upon suitable legs 4, 5 and 6, at each side. 70

The base plate is horizontal and the dies 7 and 8 which together form the mold, are arranged at one end thereof, adjacent to the metal pot 9. As relatively great pressure or power is required to hold the two parts of the mold closed against the pressure of the metal, I provide the frame with a strong rigid upright column or post 10 preferably cast integrally with the frame and arranged adjacent to the metal pot 9 and against 75 which the mold is held closed, I also provide a strong rigid post or upright 11 secured rigidly to the frame at the opposite end of the base plate 2. Between these two uprights I arrange the dies and the mechanism for operating them and for holding them closed with sufficient pressure. To strengthen these uprights I rigidly brace their upper ends apart and tie them together 80 by means of the adjustable tie rod 12. While 85 I have illustrated the die as made up of two die members 7 and 8 it should be understood that it may consist of a larger number of separable parts and indeed I have illustrated other movable parts in addition to 100 the parts 7 and 8.

The molds parts 7 and 8 each contain a portion of the mold in which the article to be cast is formed, and they are formed to close tightly together upon a median plane when 105 the die is ready for the molten metal.

I arrange the two mold parts upon the base plate 2 in close proximity to the column or post 10, the back of the member 7 being positioned against the face of the post. The 110 die parts 7 and 8 are suitably held and guided to cause them, when closed, to exactly register to properly form the article being cast. I preferably secure the die part 7 rigidly against the face of the column 10 115 and I also preferably make the mold space 14 in this part of less depth than the mold space 15 in the part 8 so that as the two parts are separated after the article is cast, the article 16 will most freely leave or to 120 be stripped from the part 7, and will remain embedded in the movable die part 8 until after the two parts are separated.

For moving the die member 8 back and forth for opening and closing the mold I 125 provide a longitudinally slidable cross head 17 mounted on the base plate 2 and guided on dovetailed guides 18 formed on the plate. The cross head is arranged centrally back of the dies and I provide an abutment 19' on 130

its forward end against which I secure a die holder 19 and to which holder I rigidly secure the rear die part 8. The die part 8 thus moves back and forth with the cross head 17.

I provide means for moving the cross head 17 and die part 8 which effects a slow starting into movement when beginning the mold opening movement of the dies and in reverse a slow closing of the dies with tremendous pressure, and also a slow stopping of the movement of the die part 8 at its extreme rear position, or when the die parts are most widely separated. The function of the slow stopping of the die in separating of the die parts will be described later. For moving the cross head in the manner described, I have provided a horizontal rotatable or oscillatory shaft 20, arranged in suitable bearings formed in the sides of the rear column or post 11 at the rear end of the plate and substantially in the horizontal plane of the center of the mold. I rigidly secure a crank plate 22 on the shaft 20 and 25 I provide a crank pin 23 projecting beyond the plate at each side to receive the rear forked ends of a connecting rod 24, the forward end of which is pivotally connected to the cross head 17 by the cross head pin 25 carried in suitable bearings 26 rigid with the cross head.

The shaft 20 is adapted to be rotated back and forth through slightly more than 180° as indicated in Fig. 3 the forked end 26' of 35 the rod 24 being bent or offset as shown adjacent to its rear end to pass the shaft. The shaft is oscillated by mechanism to be described later.

The metal pot 9 has two compartments 40 for the molten metal, the larger one 27 contains a supply of molten metal, and the smaller one 28, which lies beneath the larger one and is in the form of a U-shaped passage, from which the molten metal is projected or shot into the mold. As stated, the passage or compartment 28 is arranged beneath the supply compartment and a port 29 connects the bottom of the supply compartment to the discharge 45 passage and through which port the discharge passage is filled. This port is valve controlled and the means for opening and closing this port will be described later.

The pot 9, as described, is arranged with 55 in the depressed part of the frame and is provided with a nozzle 30 adapted to be pressed against the back of the die member 7 to make a tight joint therewith at the time that the metal is forced into the mold. This 60 die member is provided with an entrance or gate passage 31 leading into the mold space in the die and through which the metal enters the mold. I arrange the nozzle 30 and the die member 7 so that the discharge passage 65 of the nozzle and the passage 31 regis-

ter when the parts are ready to have the metal forced into the mold.

The metal which fills the passage 31 in the die member 7 if allowed to solidify in place will produce what is known as a gate or sprue and one feature of my invention relates to means for cutting off or removing this sprue in advance of separating the two parts of the die, this mechanism will be described later.

To bring the nozzle 30 into contact with the die member 7 I mount the pot for a slight movement back and forth from and toward the die. For this purpose I provide a guide stud 32 projecting rearwardly from the column 10 and over the pot and I provide a grooved bearing roller 33 mounted on a horizontal pin 34 fixed in standards 35 rising from the top plate 36 of the casing or box 37 within which the pot is inclosed. I inclose the pot within the box 37 to better apply the heat from the gas burner with which I maintain the metal in molten condition. I provide burners 38 in the lower part of the box 37 beneath the pot. These burners are 90 on parallel burner pipes 39 and are controlled by valves 40. A single fuel supply pipe 41 supplies fuel to all of the pipes 39 through the connections 42 and I provide gas and air pipes 43 and 44 for supplying the fuel to the T 45 for distribution to the connections 42. I rigidly connect the gas supply system to the box 37 by means of the threaded connection 46, so that the burners and supply pipe move with the box and the metal pot, as the pot is moved back and forth. From the upper part of the T 45 I run a burner pipe 45 around the box 37 to the nozzle 30 for keeping it hot during the 100 operation of the machine.

Besides the roller 33 for supporting the forward or nozzle end of the pot, I support the rear end upon a pair of vertically arranged side bars 47, one at each side and mounted at their lower ends on a transverse horizontal shaft 48. Their upper ends are pivotally connected to the pot by means of a horizontal shaft 48 which is carried in a central bracket 49 on the rear upper part of the pot. The bars 47 extend down through suitable openings provided in the depressed portion 3 of the bed plate. The upper ends of the side bars 47 are notched to receive the ends of the shaft 48 and to permit the easy removal of the pot and its casing, and they are held laterally against shoulders 50 by cotter pins 50' in the outer ends of the shaft 48. By swinging the bars 47 back and forth the pot is moved back and forth on the bearing stud 32.

Just above the depressed portion 3 of the bed plate I cross-connect the bars 47 by a horizontal bar 51 which I provide with solid pins or bearings 52 on its ends, entering holes in said bars, see Fig. 5, and for swing-

ing the bars 47 back and forth, I connect this bar with the operating cams of the machine as hereinafter described.

- For controlling the port opening 29 in the bottom of the supply compartment 27 of the metal pot, I provide a vertical needle valve 52 which is long enough to extend up through the cover of the pot and centrally through a guide bracket 53 rigid with the cover. A cylindrical bearing member or guide sleeve 54 slides up and down in the guide bracket and is provided with a central hole to receive the stem of the valve. Above the bearing member 54 a cotter pin 55 is inserted through a hole in the valve stem adapted to contact with the upper end of the bearing member so that when the bearing member is lifted the valve is also lifted. For moving the valve up and down I provide a bell crank 56 pivotally mounted at its elbow on a horizontal pin 57 mounted in the upper ends of the standards 35. The bell crank has a short arm 58 which extends rearwardly and is bifurcated to receive the valve stem. It is adapted to contact with the lower end of the bearing sleeve 54 and lift the valve. The bell crank has a relatively long arm 57' which extends substantially vertically and is pivotally mounted at its upper end on a fixed pin 59 carried by the free end of a bracket 60, rigidly carried by the post 10. The bracket 60 is rigidly mounted on the column 10 by means of a plate 62 bolted to the column 10 by a screw bolt 63 and the nuts which secure the tension rod 12 in place. As the pot is moved back and forth the bell crank is swung upon its pivot and the rear end of the short arm is raised and lowered.
- To cause the bell crank to close the valve I provide a compression spring 64 on the valve stem beneath the short arm of the bell crank, arranged between an upper washer 65 and a lower washer 66 and I provide a cotter pin 67 projecting through a suitable hole in the valve stem, immediately below the lower washer 66. The two cotter pins on the valve stem provide two stops or shoulders for opening and closing the valve.
- When the pot moves forward to close against the die the bell crank is swung in such a manner that the forked end is depressed and it yieldingly depresses the valve through the spring 64 and lower cotter pin and should the valve close before the pot reaches its final position the spring 64 avoids any undue strain on the valve stem. The reverse movement of the pot lifts the valve through the medium of the bearing sleeve and upper cotter pin. The upper and lower edges of the forked end of the bell crank are rounded as shown for the proper contact with the bearing sleeve and the upper washer.
- To force the metal out of the delivery passage 28 I provide a connection and mech-

anism by which, at the right moment I force air at high pressure into the rear end 68 of the passage 28. For this purpose I provide an air pipe 69 controlled by a hand valve 70 and an automatically operated valve 71, 70 which receives air under pressure from a supply pipe 72. The mechanism for operating and timing the valve mechanism 71 will be described later.

To produce the necessary movement of the several parts of the machine in their proper order or time relation, I provide a pair of cam drums 80 81, mounted on a shaft 82 mounted for rotation in bearings 83 and 84 carried by auxiliary frame members 85 and 86 respectively said auxiliary frames having arms by which they are secured to the legs 5 and 6 of the frame, as shown in Figs. 1 and 2. These two drums are bolted together adjacent to their hubs by longitudinal bolts 87, 85 so that they rotate together. To drive the drums I provide an internal gear 88 on the drum 81 and I provide a pinion 89 meshing therewith and mounted on the inner end of a horizontal shaft 90 rotatably mounted in the bearing 91 carried by the auxiliary frame plate 86. I apply power through a belt pulley 92 carried by the outer end of the horizontal shaft 90 the means for controlling the application of power to the belt pulley will be described later.

For oscillating the shaft 20 to effect the movement of the dies I provide the adjacent ends of the cam drums with similar co-operating cam grooves 93 and 94 respectively, in which I mount cam rollers 95 and 96 respectively, said cam rollers being mounted on a short shaft or pin 97 and I provide a vertically movable lever 98 arranged between the adjacent ends of the cam drums and in which the pin or shaft 97 is mounted between its ends. The lever 98 is pivotally mounted at its rear end 99 at the lower end of a bracket 100 depending from the under side of the plate 2. The forward end 101 of the lever projects beneath the shaft 20 and I transmit motion from the rear end of the lever to the shaft 20 by means of a toothed rack 102 which meshes with a co-operating gear 103 which 105 I form upon the outer edge of the crank disk 22. The lower end of the rack 102 is pivotally connected to the end of the lever 98 and as the lever 98 is moved up and down by the cam rollers 95 and 96 the rack 102 is likewise moved up and down and the shaft 90 is oscillated back and forth. I hold the rack in proper mesh by means of an anti-friction roller 104 which presses against the back of the rack adjacent to 115 the gear 103. For the purpose of avoiding possible accidents I provide a tubular casing 105 into which the upper end of the rack projects as it moves up and down. As stated hereinbefore, the shaft 20 oscillates 120

65 130

through an angle of slightly more than 180° moving the crank pin 23 from a position substantially directly in front of the shaft 20 when the dies are closed, to a position 5 substantially directly behind the shaft 20 when the dies are open. The pin 23 rises slightly above the direct line of pressure when the dies are closed, thus in effect providing a toggle lever which closes the dies 10 with great pressure and holds them locked in closed position.

One valuable feature of this mechanism which I have provided for opening and closing the dies lies in the fact that the pin 23 15 travels in the arc of the circle which approaches a line at right angles to the line of movement of the dies as it approaches each limit of the movement of the dies.

This arrangement necessarily results in a 20 relatively slow opening of the dies and a relatively slow stopping of the opening movement as the movable die reaches the limit of its opening movement. As the movable die 8 begins its opening movement, it 25 carries with it, as hereinbefore explained, the article 16, which has been cast and strips it out of the fixed die 7. The relatively slow moving of the die 8 at this point results in opening the die 8 with great force 30 and also results in the slow and easy parting of the article 16 from the fixed die 7.

For the purpose of adjusting the movement of the movable die 8 so that it will 35 properly close against the fixed die 7 to make a pressure tight joint therewith I make the connecting rod 24 adjustable as to length. For this purpose I connect the forward end 105 of the connecting rod with the pin 25 on the cross head by means of a 40 threaded rod 106, the threaded end of which projects through a collar formed on the forward end of the connecting rod 24 and is held therein by nuts 107.

To strip the cast article 16 from the movable die 8 I provide a plurality of horizontally arranged stripping pins 109 (see Fig. 7) carried on a plate 110 within the die holder 19. The plate in turn is rigidly mounted on the inner end of a horizontal 50 tube 111 which projects centrally from the die and over the cross head 17. The tube is supported in horizontal position by an elongated hub 112 projecting from the die holder 19. To effect a relative movement of 55 the stripper pins and die member 8 to strip the casting out of the die member I provide a rigid upstanding bracket 113 secured upon the plate 2 of the machine frame by means of a T-head bolt 114 the head of which engages 60 under ledges 115 rigid with the die plate and by means of which the bracket 113 can be adjusted on the plate 2 from and toward the mold to properly adjust the relative 65 positions of the stripper pins and the die member 8 when the die is closed. To pro-

vide space for this bracket 113 I provide the cross head 17 with an elongated central opening 116 as best shown in Fig. 4. The rear end of the tube 111 projects through the bracket 113 and I provide thereon an 70 adjustable collar 117 to prevent the stripper pins projecting into the mold space when the dies are closed. The collar is secured by a set screw 118. I provide an enlarged washer 119 on the tube 111 between the 75 collar 117 and the rear face of the bracket 113. When the cross head moves the die 8 to its closed position the collar 117 effects the withdrawal of the stripper pins from the die to casting position as shown in Fig. 80 7. When in this position the plate 110 contacts with the back wall of the die holder and the pins are long enough to project through the wall of the die member 8, their inner ends being flush with the mold 85 face.

When the die is opened the tube 111 slides rearwardly through the bracket 113 until the die approaches the limit of its outward movement, at which point, as the die is moving relatively slowly, I arrange mechanism 90 to force the stripper pins through the die 8 to force the casting out of the die. For this purpose I provide an adjustable set collar 120 on the tube 111 between its ends and 95 adjust this collar so that it will contact with the adjacent face of the fixed bracket 113 at a point sufficiently in advance of the extreme outer position of the die member 8 to hold the stripper pins stationary and to cause 100 them to force the casting out of the die, just as the die is coming to a stop in its rearward movement.

I thus effect the stripping of the casting from the fixed die 7 with a powerful slow 105 movement and I also effect the stripping of the casting from the die member 8 by a similar movement.

One feature as hereinbefore explained relates particularly to the cutting off of the sprue, and the particular mechanism which I have devised for this purpose has a special relation to a special form of casting or article. This form of article is one which is to be provided with a through hole and which 110 hole can be arranged to be produced substantially in line with the passage 31 through which the metal enters the mold. In other words, this special feature relates to the production of small gears, wheels, 115 pinions and similar articles whether symmetrical or not having a hole extending 120 through the body of the casting.

To effect the cutting off of the sprue I provide a rod or plunger 121 mounted centrally in the die member 8 in alignment with the passage 31 and extending through the tube 111. This plunger is movable relatively to the die and immediately after the 125 mold is filled with molten metal and before 130

the metal in the passage 31 solidifies I force this plunger forward so that its free end 122 projects into the mouth of the opening 31 as best shown in Fig. 8. I cone the inner 5 end 122 of this plunger so that it will readily enter into the mouth of the passage 31 and I make the plunger of a diameter to substantially fill the mouth of the passage so that when the plunger is in the position 10 shown in Fig. 8 the casting is completely severed from the metal which lies within the passage 31. As the nozzle 30 is maintained hot and as I arrange the machine so that the casting pressure is removed from 15 the metal just after the plunger 121 cuts off the sprue the metal in the passage 31 falls back into the passage 28 of the pot and the casting is entirely free at this point of any fins or projections.

20 To effect this relative movement of the plunger 121 to cut off the sprue I provide mechanism as follows, reference being had particularly to Figs. 3, 7, 8 and 9. I rigidly mount the rear end of the plunger 121 in a 25 bracket 123, making it adjustable in the bracket by means of set nuts 124, the bracket being movably mounted upon the cross head 17. The bracket is arranged centrally on the cross head between the bearings 26, in 30 which the cross head pin 25 is mounted and it is guided in its back and forth movement by these bearings. For moving the bracket relatively to the cross head I provide a gear rack 125 on the lower face of the bracket 35 and a pinion 126 formed on the inner end of the horizontal shaft 127 mounted in the cross head itself. To hold this shaft against endwise movement I provide a set screw 128 in the cross head the inner end of which 40 enters a circumferential groove 129 in the shaft. The bracket 123 is held down in proper mesh with the pinion by overhanging guides 129' on the bearings 26. It will now be clear that by rotating the shaft 127 45 the plunger 121 can be moved relatively to the cross-head and the dies. To effect the result desired in the cutting off of the sprue the plunger 121 must be moved forward by a sharp quick movement before the dies begin to open, said movement being in the 50 form of a hammer blow.

To effect the hammer-like blow desired, I provide an arm 130 secured to the outer end of the shaft 127 and preferably formed integrally therewith, said arm extending substantially vertically and a tension spring 131 having one end attached to the arm above the shaft and the other end secured to a post or pin 132 rigid with the cross head 17 and 55 arranged forward of the shaft 127. The spring 131 tends to hold the plunger 121 at the forward limit of its movement, relatively to the cross head. To limit the forward movement of the plunger relative to 60 the cross head I provide a stop pin 133 on

the cross head and a coöperating stop projection 134 on the lower end of the arm 130. These coöperating stops are in contact, as shown in Fig. 8, when the plunger is in its forward position relative to the dies. 70

To swing the arm 130 rearwardly, thus drawing back the plunger and lengthening the spring 131 I provide a latch stop 135 in the path of a projection 136 carried by the upper end of the arm 130 and projecting 75 outwardly therefrom. The latch stop 135 is pivotally mounted on a horizontal pin 136' to swing in a vertical plane and is adapted to permit the stop 136 to pass the latch as the stop moves rearwardly and to engage 80 and hold the stop 136 as the stop moves forward again. I mount the latch with its pivot in the lower end of a set collar 137, which I mount upon a longitudinal horizontal shaft 138 arranged at a suitable height and carried in carrying brackets 139 secured upon the plate 2 and I provide means for rotating the shaft slightly in its bearings to slide the latch 135 off of the pin 136 at the instant it is desired to force the plunger forwardly 85 to cut the sprue. For this purpose I provide a crank arm rigidly mounted on the shaft 138 and extending downwardly therefrom and I provide an arm 141 pivotally mounted at its lower end in brackets 142 90 projecting outwardly from the auxiliary frame plate 85 and I operatively connect the free ends of these two arms by the link 143 so that as the arm 141 is swung out and in, the shaft 138 will be rotated in its bearings. I normally hold the arm 141 at the inner limit of its movement by a tension spring 144 connected between the upper 95 end of the arm and the frame of the machine. To force the arm 141 outwardly and 100 thus release the pin 136 from the latch 135, I provide a horizontal plunger 145 mounted to move out and in relatively to the frame of the machine, provided in its outer end with a transverse notch 146 to engage the lower edge of the horizontal bar 147 forming part of the lever 141. This plunger 145 is mounted for endwise movement in a suitable opening provided in a bracket 148 secured to the auxiliary frame member by a 110 bolt 149. I provide the plunger with a collar 150 at its outer end, adapted to contact with the bracket and the collar acts as a stop to limit the inward movement of the arm 141. To force the plunger outwardly 120 against the action of the spring 144 and thus effect a release of the pin 136 from the latch 135, I provide a V-shaped cam projection 151 on the inner cylindrical surface of the cam drum 80 arranged to contact with the inner 125 end of the plunger and force it outwardly, the plunger being provided with an anti-friction roller 152 arranged for contact with the cam surface. I so arrange the cam projection 151 relatively to the cam slot 94 130

which effects the opening and closing of the dies, that the pin 136 on the arm 130 is released from the latch 135 just before the dies 8 begin the opening movement, at which 5 time the mold has been filled.

As described hereinbefore, the pot 9 has a slight movement back and forth for positioning the nozzle 30 against the die 7 and holding it there with sufficient force to properly control the metal and for relieving it 10 from such position and permitting the metal to drop back into the discharge passage 28. To effect this slight movement of the pot and hold it in casting position with sufficient 15 force, I provide a bellcrank lever 154 (see Fig. 3) pivotally mounted at its heel on a horizontal shaft 155 mounted at its ends in the legs 5 and arranged centrally under the base plate 2. It has a relatively long horizontal arm 156 extending rearwardly between the cam drums and adapted to be engaged by a cam roller 157 arranged between the two cam drums and mounted upon a bearing pin 158 carried by said drums, said 20 roller being arranged between the cam groove 94 and the shaft 82 upon which the drums are mounted. I hold this arm at the upper limit of its movement by means of a tension spring 158' attached at its lower end 25 to the rear end of the arm 156 and at its upper end to a projection 159 on the frame of the machine. The other arm 160 of the bell crank 154 is relatively short; it extends vertically and engages at its upper end a 30 horizontal shaft or rod 161 which extends across the machine and is mounted at its end in vertically extending swinging bars 162, one at each side. The lower ends of the bars 162 are pivotally mounted on the 35 cross shaft 155. I connect the upper ends of the bars 162 by a horizontal shaft or bar 163, the construction in effect providing a swinging frame by which the movement of the bell crank is transferred to the two sides 40 of the machine and which frame forms virtually an extension of the short arm 160. For connecting the bellcrank 154 with the crossbar 51 which connects the vertical swinging bars 47 on the upper ends of which 45 the pot rests I provide longitudinal horizontal side bars 164 connected at their rear ends with the cross shaft or bar 163 and at their forward ends rigidly connected to and spaced apart by a crossbar 165 (see Fig. 5) 50 which in turn is connected to the cross bar 51 by a centrally disposed screw bolt 166. The bolt 166 passes through a smooth hole in the bar 165 and screws into a threaded hole provided in the bar 51. For holding 55 the bars 165 and 51 rigidly together and adjusting them as to relative position, I provide set screws 167, one at each end of the bar 165 extending through threaded holes provided therein and their ends adapted to 60 contact with the adjacent side of the bar 51. 65

The forward ends of the side bars 164 are rigidly connected to the crossbar 165 by the screws 168. It will now be clear that by adjusting the screw bolt 166 and the set screws 167 I can effect a final adjustment of the pot 70 9 in relation to the bell crank 154 to cause the bell crank to properly position the nozzle against the fixed die 7.

As hereinbefore mentioned, I provide a shield 170 to protect the workmen against 75 the possibility of the metal being forced into the die without the die being properly closed. This shield comprises a sheet metal cover of a size to properly inclose the working parts of the machine and adapted to be raised and 80 lowered automatically. The shield is guided in its up and down movement upon guides 171 rising from the four corners of the machine which are engaged by the sleeves 85 172 on the shield.

The upper ends of the guides 171 are connected by a light framework 173 upon which are provided suitable grooved pulleys 174 to guide lifting cables 175 for lifting and lowering the shield. 90

The casing is heavy enough to drop by gravity and is lifted by means of a substantially horizontally disposed swinging lever 176 pivotally mounted for swinging up and down on a transversely arranged horizontal shaft 177. There are two of the arms 176 one at each side of the machine and each carries in its free end a grooved pulley 178 for receiving the two cables 175 connected to that side of the casing. The arms 176 are pinned to the shaft 177 and I oscillate the shaft and move the arms up and down by means of a crank arm 180 pinned to one end of the shaft 177 and having an operating bar 181 pivotally connected to its free end. 100 The opposite end of the rod or bar 181 is arranged adjacent to the cam shaft 82 upon which I secure an eccentric 182 for contact with the roller 183 carried in the free end of the bar 181. To guide the bar 181 in its 110 back and forth movement I provide the link 184 pivotally connected at its lower end to the bar 181 adjacent to the end in which the roller 183 is mounted, and at its upper end to the frame of the machine. The weight 115 of the casing 170 holds the roller 183 in contact with the eccentric 182 at all times, and as the cam shaft 82 rotates, the eccentric 182 forces the bar 181 rearwardly and the operating arms 176 downwardly. The free ends 120 of the cables 175 pass around the pulleys 178 and are attached at their free ends to the frame of the machine at point 185 above the arms 176 and consequently the pulleys or sheaves 178 rest in loops of the cables which 125 they lengthen when the bar 181 is forced rearwardly and by thus lengthening these loops they raise the shield in an obvious manner. I so adjust the position of the eccentric 182 relatively to the cam groove 94, 130

which effects the closing of the dies, so that the shield is at the lower limit of its movement and operative to protect the workmen when the dies are closed. Suitable openings 5 186 are provided in the die plate 2 for the cables 175.

As explained hereinbefore, I provide other die parts and means for moving them than the main die parts 7 and 8 and I have particularly illustrated in Figs. 10, 11 and 12 the parts typical of such additional die parts. I have illustrated what may be called core pins 185' and 186' which are arranged to be projected transversely into the mold space 10 for producing holes or openings in the article 15 to be cast. These pins are arranged at opposite sides of the machine and are adapted to be moved out and in simultaneously and as the operating mechanism of the two 20 pins are substantially duplicates of each other, being merely right and left, a description of the one will suffice for the other. The pin 185' is mounted in a cross head 187 movable transversely of the machine on guides 25 188. The cross head is linked by a short link 189 to the forward end of a horizontally swinging lever which has its rear end positioned substantially vertically above the cam shaft 82 and projects above the cam drum 30 80. I arrange a suitable cam groove 191 on the cylindrical outer surface of the cam drum 80 and I provide a cam roller 192 on the rear end of the lever 190 fitting within the cam groove 191 and whereby the lever 190 is 35 adapted to be swung horizontally to move the cross head 187 back and forth. The lever is supported in position against the under side of the plate 2 by straps 193 which are secured to the plate, forming slots in which 40 both of the levers 190 can operate. The lever 190 is pivotally mounted on the die plate by a pin 194 which is dropped into one of a series of holes 195, provided in the die plate and enters one of the series of holes 196 45 provided in the lever 190. These series of holes permits the adjustment of the fulcrum of the lever from or toward the roller 192 and thus adjusts the movement of the cross head and the die pins 185'. 50 I so arrange the cam groove 191 with its offset cam surfaces in such relation to the cam groove 94 that the die parts or pins 185' and 186' are moved inwardly after the die parts 7 and 8 are closed and are again moved 55 outwardly before the die parts are separated.

It is desirable that the pin 185' or like die parts be movable relatively to the mold so as to cause the same to properly register. 60 For this purpose I mount the pin 185' on a plate 185^a in turn fitting within a dovetailed groove 185^b. The groove is formed in the face of the bracket 187, and I adjustably mount the bracket on a base 187^a by 65 T-head bolts 187^b whose heads engage in

T-slots 187^c in the base 187^a. I provide a simple positive form of adjusting and locking device consisting of a threaded bolt 187^d arranged parallel with the guides. Its threaded end enters a threaded hole 187^e in the base 187^a and it has a rigid fixed collar 187^f between its ends which engages in a shouldered groove 187^g in the base 187^a so that as the bolt or screw 187^d is rotated the bracket 187 is adjusted on the base 187^a. 70 I connect the base 187^a to the forward end of the lever 190 by a short link 189 pivotally connected at one end to the end of the lever by a shouldered pin 190^b pivotally connected to the base 187^a by a pin 190^c which screws 80 rigidly into the base 187^a and projects a slot 190^d provided in the base plate 2. 75

As explained hereinbefore, power is derived for the operation of the machine through the pulley 92 which is engaged by 85 the belt 197.

For starting and stopping the machine I provide a horizontal shaft 198 extending across the machine and mounted at its ends in the legs 5. This shaft 198 carries a hand lever 199 rigidly mounted thereon and projecting upwardly at one side of the machine in convenient position to be grasped by the operator. I arrange a crescent 200 adjacent to the lever 199 and having a central notch 95 201 and side notches 202 and 203. These notches are adapted to receive the inner end of a sliding stop 204 carried by the hand lever 199 and normally thrust inwardly by means of a spring 205. The center notch 100 201 may be termed a neutral notch for when the lever is in a central position the machine is at rest. The right hand notch 202 is the forward running notch because when the lever is shifted with the dog in 105 this notch the machine runs in a forwardly direction; when the lever is reversed to enter the dog in the lefthand notch 203, the machine runs backward.

Adjacent to the crescent 200 I arrange 110 a quadrant 206 having notches 206' in its edge registering with the notches in the crescent 200 and which have inclined or cam shaped ends and adapted, when centrally positioned, to permit the dog or stop 204 entering any one of the three notches and adapted when moved from its central position to engage the dog and raise it sufficiently to free it from the notch in which it is placed; that is, from either of the end 120 notches to permit the handle 199 to return to its central position. For swinging the quadrant 206 for releasing the handle lever 199 I provide a short vertical lever 207 mounted on the outer end of a short shaft 125 208 carried by the auxiliary frame 85 and having at its inner end a crank arm 209 carrying at its free end an anti-friction roller 210 adapted for engagement with a double coned cam projection 211 carried by 130

the cylindrical inner surface of the cam drum 80. The free end of the arm 207 is linked to the quadrant 206 by means of a connecting link 212, so that when the cam projection 211 strikes the cam roller 210 the quadrant 206 moves sufficiently to free the dog 204 from one of the side notches and permits the hand lever 199 to return to the center notch. I provide a stop 213 on the auxiliary frame 85 in the path of a projection 214 on the lower end of the lever 207 to limit the movement of the quadrant 206 in one direction, and to normally hold the quadrant in such position with the stops engaged, I provide a tension spring 215 connected at one end to the free end of the lever 207 and at the other end to the frame of the machine.

The shaft 198 extends through the machine from side to side and at its other end I mount a swinging lever or crank arm 216 which stands vertically when the machine is at rest and is adapted to be swung forward or back with the hand lever 199 for starting the machine. Adjacent to the free end of the lever 216 I secure a cam cross bar 217 projecting from both sides of the lever 216, its upper edge 218 adapted to engage an anti-friction roller 219 in the free end of a lever 220 which is pivotally mounted on the frame of the machine at 221. This lever 220 carries a brake shoe 222 adapted to engage the rim of the pulley 92 when the lever 216 is in its central or neutral position and hold the machine against operation. When the lever is moved into one of the end notches, as indicated on Fig. 2, in full lines, the arm 217 lifts the lever 220 and frees the pulley 92 from the brake 222. The free end of the arm 216 is connected by means of a link 223 to the free end 224 of the horizontally swinging lever 225 pivotally mounted on the top of the base plate 2. This lever 225 is linked to a second horizontally swinging lever 226 by a horizontal link 227. The horizontal swinging lever 226 is mounted on the lower end of a vertical shaft 228 which extends upwardly above the machine and is connected to operate suitable clutch mechanism, not shown, for controlling the operation of power to run the belt 197 to operate the machine either forward or backward as desired and as designated by the position of the hand controlled lever 199.

For positively throwing the hand controlled lever 199 to its central neutral position from either of its operating positions and for applying the brake with sufficient force I provide a strong tension spring 229 connected at one end to the free end 230 of the brake lever 220 and at its other end to a bracket 231 rigid with the frame of the machine. The spring 229 holds the lever 220 and its roller 219 tightly against the cross bar 217 and is adapted to force the arm

216 to a central position from either side and thus carry the hand lever 199 to its neutral position, and at such time the spring 229 holds the brake shoe 222 against the bell pulley 92.

In the operation of the machine the most dangerous feature is the possibility that the air pressure may be applied to the molten metal to force the metal out of the pot before the die is properly closed, and for the purpose of affording absolute protection to the workmen should such an accident occur, I prevent the operation of the valve mechanism 71 for the application of the air until the casing 170 reaches its lowermost or protecting position. For this purpose I provide a vertical lever 232 pivoted between its ends at 233 upon the frame of the machine and I provide a vertically disposed cam surface 234 on the adjacent side of the casing 170, the upper end of the lever 232 being provided with an anti-friction roller 235 for contact with this surface. The valve mechanism 71 is provided with a valve stem 236 and for moving the valve stem to operate the valve and admit air to the pot I provide a link 237 connected at one end to the free end of the valve stem 236 and at its other end to a vertically swinging lever 238 pivotally mounted at one end upon the frame of the machine and linked at its other end 239 to the lower end 240 of the lever 232 by a link 241. A tension spring 242 is also attached to the free end of the lever 238 and tends to hold the same forwardly with the anti-friction roller 235 of the lever 232 in contact with the cam surface 234 on the casing and also tends to move the valve rod 237 in a direction to admit air to the pot. The cam surface 234 on the casing is curved forwardly at its upper end 243 to permit the upper end of the lever 232 to swing forwardly when the casing reaches its lowermost position and permit the spring 242 to set the valve to admit air to the pot.

I do not depend wholly upon this safety device preventing the premature opening of the valve, but I provide a cam surface 244 on the periphery of the cam drum 81 adapted to engage a cam roller 245 on the free end of a swinging arm 246 secured rigidly upon the inner end of a horizontal shaft 247 upon which the vertically swinging lever 238 is mounted. The cam surface 244 extends nearly around the periphery of the cylinder but is cut away at 244' to provide a depressed portion to permit the arm 246 to swing inwardly. The depressed cam surface 244' permits the lever 238 to swing to open the air valve in response to the action of the spring 242. Should the casing not be at its protecting position when the arm 246 is free to swing inwardly then the lever 232 and cam surface 234 will prevent the opening of the air valve. It should be understood that

the pot casing is provided with a suitable door 37' to give access to the burners and also with a suitable cover 248 to permit the feeding of metal into the pot. I preferably lock the cover closed by a weighted lever 249 pivotally mounted between its ends on the free edge of the cover between upwardly projecting lugs 250 and provided with a hook 251 on its lower edge adapted to engage beneath a staple or loop 252 rigid with the top of the pot. The lever is provided with an outwardly extending handle which can be grasped to lift the cover 248 and the inner end of the lever is provided with a downwardly extending projection 254 adapted to contact with the upper surface of the cover when the handle part is lifted and thus hold the lever in rigid lifting position.

The cam controlled sequence of operations of the machine is such that when the hand lever 199 is moved to the right hand notch from the center notch the mechanism applies power to the belt to run the machine in a forward direction, the die part 8 is first closed against the die part 7, the transversely movable die parts 185' and 186', if they are used, are then moved inwardly, the pot is then swung forwardly to bring the nozzle into proper contact with the die part 7. In the meantime the casing is being lowered and when the other parts are in proper position the casing has reached its lowermost position and permits the valve mechanism to be operated as soon as the cam 244 permits the lever 238 to swing and permits the operation of the valve mechanism by the spring. As the depressed cam surface 244' is relatively short the valve can be opened only during a small angular movement of the drum shaft, but as soon as the raised cam surface 244' contacts with the roller 245 the valve is positively closed. As soon as this point is reached the plunger 121 is forced through the sprue opening to cut the sprue off and then the opening movement of the die part 8 begins stripping the casting out of the die part 7. During this time the casing also is being raised to its upper position. The opening movement of the dies continues and as the die part 8 nears the outer limit of its movement the stripper pins 109 are operated to strip the casting out of the die part 8.

The pot casing is provided with suitable vent pipes 256 rising beneath the hood or casing 170 to permit the escape of the gases of combustion from the pot casing beneath the shield 170. The shield is provided with a suitable telescopic ventpipe 255 to carry away the fumes and to permit the up and down movement of the shield.

I claim:

1. In a power operated die casting machine, two coöperating mold forming dies,

power operated means for moving one die 65 toward and from the other die to close and open the mold, and means for causing the opening movement to begin and end relatively slowly.

2. In a die casting machine, two relatively 70 movable mold parts, means for separating the two parts with a movement which begins relatively slowly and gradually increases to a maximum substantially midway of the extent of movement and then decreases gradually to the limit of its movement, and means for stripping the casting from the mold while the said movement is decreasing.

3. In a die casting machine, a fixed die part and a coöperating relatively movable 80 die part, a shaft rotatable back and forth through substantially 180°, a crank pin carried by the shaft, the positions of rest of the pin being substantially in alinement with said movable die parts, connections between 85 the pin and the movable die part for moving the die part back and forth as the shaft oscillates, and whereby the die part starts and stops relatively slowly.

4. In a die casting machine, a fixed die 90 part and a coöperating movable die part, a shaft rotatable back and forth through substantially 180°, a crank pin carried by the shaft the positions of rest of the pin being substantially in alinement with the movement of said movable die part, and means connecting the crank pin with the movable die part whereby the movable die part starts and stops relatively slowly; and strippers carried by the movable die part for stripping the casting therefrom as it stops.

5. In a die casting machine, a die mold adapted to be opened and closed horizontally, the mold provided with a horizontal inlet passage, a metal pot having a delivery 105 nozzle and adapted to be moved horizontally to position the nozzle against the mold in register with said passage, a cam shaft operatively connected with the mold and the pot for closing the mold and for moving the 110 pot, and a plunger carried by the mold adapted to cut off communication between said passage and the mold space, and cam means carried by said shaft for effecting the cutting off movement of said plunger before 115 the mold begins to open.

6. In a die casting machine, a die part having an inlet passage for molten metal, and a movable part for closing and opening the mold, a plunger carried by the movable 120 part and adapted to be projected through the mold space into the mouth of said passage to cut off communication between same, means normally tending to hold the plunger in projected position, means for withdrawing the plunger as the mold is closed, and means for releasing the plunger before the mold is opened.

7. In a die casting machine, a die part having an inlet passage for molten metal, and a movable part for closing and opening the mold, a plunger carried by the movable part and adapted to be projected through the mold space into the mouth of said passage to cut off communication between same, a cam shaft, cam means for moving the movable mold part back and forth, means connected with the movable mold part for normally holding said plunger in relatively projected position, a relatively rigid stop for effecting the withdrawal of the plunger as the mold closes, and cam means for releasing the plunger from the stop before the mold opens. 65
8. In a die casting machine, a mold comprising a fixed part and a relatively movable part, a rotatable shaft for operating the movable part, a crosshead carrying the movable part, and a connecting rod operatively joining the crosshead and the shaft, the fixed part having an inlet passage to admit the molten metal to the mold, a plunger carried by the movable part adapted to be projected into said passage, means carried by the crosshead for normally holding the plunger in relatively projected position, means carried by the machine for holding the plunger back as the mold is closed, and cam means for releasing the plunger holding means before the mold is opened. 70
9. In a die casting machine, a die part movable back and forth to open and close the mold, a shaft oscillatable through substantially 180° and means operatively connecting the shaft and die part for moving the same back and forth, a cam shaft, cam means for oscillating the first mentioned shaft back and forth, a metal pot movable horizontally to contact with the mold, cam means on the cam shaft for moving the pot back and forth, means carried by the mold for closing the connection between the pot and the mold space, and cam means carried by the cam shaft for causing the connection to be closed before the pot is moved away from the mold. 75
10. In a die casting machine, a die mold having an inlet passage for molten metal, a sprue cutter carried by the mold, means for moving said cutter relatively to said mold to cause it to enter said passage, said means adapted to apply its maximum force at the beginning of the movement of said cutter. 80
11. In a die casting machine, a metal pot having a delivery passage, and a reservoir communicating with said passage, a valve controlling said communication, said pot movable horizontally for positioning it against a mold, a bell crank lever pivotally mounted on a fixed bracket on the machine and also pivotally connected to the pot, and an arm on said lever adapted to depress the valve to close such communication as the pot moves to casting position and to lift the valve to open the passage as the pot moves from casting position. 85
12. In a die casting machine, a metal pot having a reservoir and a metal delivery passage, a port connecting the lower part of the reservoir and the passage, a valve extending through the cover of the pot and controlling such port, a guide for the upper end of the valve, a vertically movable sleeve in said guide, a compression spring surrounding the valve stem below said sleeve, a shoulder on the valve above the sleeve and a shoulder on the valve below the spring, a lever engaging the lower end of the sleeve and the upper end of the spring and adapted to move the valve up and down to open and close the port, the lever pivotally mounted between its ends on the cover of the pot and pivotally mounted at its opposite end in a bracket fixed to the frame of the machine, whereby when the pot is moved forward to casting position and backward from casting position, the port is closed and opened respectively. 90
13. In a die casting machine, a metal pot movable for closing the nozzle of the pot against the mold, a horizontal guide for the nozzle end of the pot and a swinging lever supporting its rear end, a cam shaft, cams and cam rods connecting said lever to the cam shaft, and an adjustable connection interposed between the cam rods and said lever for effecting the relative position of the pot to cause the cam to position the nozzle of the pot against the mold with the desired pressure. 95
14. In a die casting machine, a die part movable to open and close the mold, cam means for effecting the movement of the die part, mechanism operatively connecting the cam means with the die part, and means interposed in said mechanism for applying greater force to move the die part at the beginning and ending of its opening movement than at the middle portion of its opening movement. 100
15. In a die casting machine, a die part movable to open and close the mold, cam means for effecting the movement of the die part, mechanism operatively connecting the cam means and the die part, said mechanism including means for effecting the relatively slow movement of the die part at the beginning and ending of its opening movement. 110
16. In a die casting machine, a die part movable to open and close the mold, cam means operatively connected to the die part for moving same, means interposed in said connection for causing the die part to move relatively slowly at the beginning and ending of its opening movement and to increase 115

the force applied to the die part at such time.

17. In a die casting machine, a die part movable to open and close the mold, cam means connected to the die part for moving same, and a toggle lever device interposed in the connection to effect the relatively slow and powerful movement of the die part at the beginning and ending of its opening movement.

18. In a die casting machine, a die part reciprocable to open and close the mold, cam means connected to the die part for reciprocating same, and a toggle lever device interposed in the connection to effect the relatively slow and powerful movement of the die part at the beginning and ending of its opening and closing movement.

19. In a die casting machine, a die part movable to open and close the mold, a shaft rotatable through substantially 180 degrees to open the mold, a pin carried by the shaft, a connecting rod mounted on the pin for moving the die part, the limiting positions of the pin being substantially in alinement with the longitudinal movement of the connecting rod, and cam means for timing the movement of the shaft.

20. In a die casting machine, a die part reciprocable to open and close the mold, a shaft rotatable back and forth through substantially 180 degrees to reciprocate said die part, a crank pin carried by the shaft, a connecting rod mounted on the pin for reciprocating the die part, the limiting positions of the pin being substantially in alinement with the longitudinal movement with the connecting rod, and cam means for oscillating the shaft.

21. In a die casting machine, a die part reciprocable to open and close the mold, a shaft rotatable back and forth through substantially 180 degrees to open and close the mold, an eccentric bearing carried by the shaft, a connecting rod mounted on the bearing and operatively connected to said die part, the positions of rest of said bearing being substantially in alinement with the line of reciprocation of the opposite end of the connecting rod, a gear carried by the shaft, a rack meshing with the gear and means for reciprocating the rack to oscillate the shaft.

22. In a die casting machine, a die part reciprocable to open and close the mold, a shaft oscillatable back and forth through substantially 180 degrees to open and close the mold, a crank pin carried by the shaft, a connecting rod mounted on the pin and operatively connected to said die part, a gear and a reciprocating rack for oscillating the shaft, and cam means for reciprocating the rack.

23. In a die casting machine, a die part

reciprocable for opening and closing the mold, a shaft oscillatable through substantially 180 degrees to open and close the mold, a crank pin carried by the shaft, a connecting rod mounted on the pin and operatively connected to said die part, a gear and a reciprocating rack for oscillating the shaft, a cam shaft, two cam drums on the shaft, the drums having co-operating cam grooves in their opposed ends, a swinging lever disposed between the drums its free end connected to said rack, and operative connection between said grooves in the drums and said lever for swinging same.

24. In a die casting machine, a die part movable back and forth to open and close the mold, a shaft oscillatable through substantially 180 degrees to open and close the mold, a crank pin carried by the shaft, a connecting rod mounted on the pin and operatively connected to said die part, a gear and a reciprocating rack for oscillating the shaft, a cam shaft, a cam drum on said cam shaft, the drum having a cam groove in its end, a swinging lever associated with the drum, its free end pivotally connected to said rack, a pin carried by the lever entering said groove and a roller on the pin, and means for holding the rack in mesh with the gear as the rack is reciprocated by the lever.

25. In a die casting machine, a die part movable to open and close the mold, a shaft oscillatable through substantially 180 degrees for effecting a relatively slow movement of said die part at the beginning and ending of its opening movement, a gear carried by the shaft, a reciprocable rack engaging the gear, a roller back of the rack holding it in mesh, cam means for reciprocating the rack, including a swinging lever pivotally connected at its free end to one end of said rack.

26. In a die casting machine, a die part movable back and forth to open and close the mold, a shaft oscillatable through substantially 180 degrees to effect the relatively slow and powerful movement of said die part at the beginning and ending of its opening movement, a crank pin carried by the shaft, a reciprocable cross head mounted on the machine and connected to the die part, a connecting rod operatively connecting the cross head and the crank pin, and means for adjusting the length of the rod to adjust the closing position and pressure of said die part.

27. In a die casting machine, a metal pot comprising a U-shaped passage and a reservoir lying between the arms thereof, a valve having a passage connecting the bottom of the reservoir with the bottom of the U-shaped passage, a die mold, a nozzle for the front end of the passage, means for support-

- ing said pot and means for moving the pot horizontally on its support to position the nozzle against the die.
28. In a die casting machine, a die mold, 5 a metal pot comprising a U-shaped passage and a reservoir lying between the arms of the passage, a valve having a passage connecting the bottom of the reservoir with the bottom of said U-shaped passage, a nozzle for the front end of the reservoir, a support for the pot, means for moving the pot horizontally to position the nozzle against the die, and means for closing said valve when the pot is moved forward.
- 15 29. In a die casting machine, a metal pot having a reservoir and a U-shaped passage lying outside of and below said reservoir, a passage connecting the bottom of the reservoir to the lower part of the U-shaped passage, a vertically movable valve controlling said passage, a discharge nozzle at the front end of said U-shaped passage, a support for said pot, a die mold, means for moving said pot horizontally back and forth on its support from and against said mold, and means 25 operable by the movement of the pot for controlling the opening and closing of said valve.
30. In a die casting machine, a die mold, 30 a metal pot having a reservoir and a U-shaped passage lying outside of and below said reservoir, a valve between the bottom of said reservoir and the passage, a discharge nozzle at the forward end of said passage, 35 a support for said pot, means for moving the pot horizontally back and forth relative to the die mold, means operable by the forward movement of the pot for closing said valve, and means for admitting fluid under 40 pressure to said passage when said valve is closed.
31. In combination, a metal pot comprising a U-shaped passage and a reservoir communicating with said passage, a valve controlling said communication, said valve comprising a valve seat secured to said pot, a 45 valve stem carried by said pot, means for moving the pot horizontally for discharging metal from said passage, and means operable by the movement of said pot to close 50 said valve upon its seat.
32. In a die casting machine, a metal pot comprising a U-shaped passage and a reservoir communicating with said passage, a valve controlling said communication, said valve comprising a valve seat in said metal pot and a vertically movable valve stem carried by the pot, a discharge nozzle at one end 55 of said passage, a die mold, means for moving said metal pot horizontally to bring said discharge nozzle into communication with said die mold, said movement causing said valve stem to be depressed to close upon said valve seat.
33. In a die casting machine, a metal pot 65 mounted to be moved back and forth horizontally, said metal pot comprising a U-shaped passage and a communicating reservoir, a valve carried by said pot for controlling the communication between the passage 70 and reservoir, a discharge nozzle at one end of the passage, a die mold adapted to be engaged by said nozzle, and cam means for moving said metal pot horizontally for engaging said nozzle with said die mold and moving said valve to close said communicating passage.
34. In a die casting machine, a base plate, a metal pot mounted thereon for movement horizontally back and forth, said metal pot 80 comprising a U-shaped passage having a nozzle at one end and an air pipe at the other, and a reservoir communicating with the passage between its ends, a valve carried by said pot for controlling said communication, and means for operating said valve by the forward movement of said metal pot 85 to close off said communication.
35. In a die casting machine, a base plate, a die mold secured thereto, a metal pot 90 mounted thereon for movement horizontally back and forth, said pot comprising a reservoir and a U-shaped passage having communication with said reservoir, valve means for closing off said communication, said 95 valve means comprising a vertically movable spring held valve stem carried by the pot, and means carried by said base plate for movably supporting said stem, a discharge nozzle at one end of said U-shaped passage, 100 means for admitting fluid under pressure at the other end of said passage, and cam means for moving the metal pot forward for bringing the nozzle into engagement with the die mold, and for admitting fluid 105 under pressure to force the metal through said nozzle, the forward movement of said pot causing movement of said valve to close off said communication in advance of the admission of said fluid pressure.
36. In a die casting machine, a frame, a cam shaft mounted on said frame, means for driving said cam shaft, coöperating parts of a die mold mounted on the frame, 110 a metal pot mounted on the frame for movement back and forth horizontally into and out of engagement with said die mold when the same is closed, said cam shaft having means thereon for closing said die mold, and having means thereon to thereafter 115 move said metal pot forward into communicating position with said die mold.
37. In a die casting machine, a frame, a die mold having a part movable for opening and closing the mold, stripper pins movable 120 through said die part, a tubular guide member carrying said pins, a sprue cutter rod projecting through said die part and

through said tubular member, a cross head on which the said mold part is carried, said tubular member longitudinally movable relative to said cross head, coöperating stops 5 on the frame and tubular member for limiting its movement in both directions, means connecting the sprue cutter with said cross head for movement therewith, and cam means carried by the frame for reciprocating the cross head.

38. In a die casting machine, a frame, a die mold on the frame comprising a fixed part, and a movable part, a member guided on the frame and carrying the movable die part, stripper pins projecting through the movable die part, a tubular member guided on said movable member and carrying said stripper pins, and a sprue cutter carried by said movable member and projecting 20 through said tubular member and through said movable die member and means for reciprocating said movable member.

39. In a die casting machine, a frame, a die mold having a part movable for opening 25 and closing the mold, stripper pins movable through said die part, a tubular member carrying said pins, a sprue cutting rod projecting through said die part and through said tubular member, a cross head reciprocal 30 on said frame and on which said mold part is carried, said tubular member longitudinally movable relatively to said cross head, said sprue cutter carried by said cross head, coöperating stops on the frame and tubular member 35 for limiting its movement in both directions, said stops arranged to cause the stripping action to occur after the mold part has been drawn back to open the mold, and means for reciprocating the cross head.

40. 40. In a die casting machine, a frame, a die mold having a part movable for opening and closing the mold, stripper pins movable through said die part, a tubular guide member carrying said pins, a sprue cutting 45 rod projecting through said die part and through said tubular member, a cross head reciprocal on said frame on which said mold

part is carried, said tubular member and said sprue cutter carried by said cross head, said tubular member longitudinally movable 50 relatively to the cross head, coöperating stops on the frame and the tubular member for limiting its movement in both directions, said stops arranged to cause the stripping action to occur as the mold part is nearing 55 the limit of its opening movement.

41. In a die casting machine, a frame, a die mold having a part movable for opening and closing the mold, stripper pins movable through said die part, a tubular guide 60 member carrying said pins, a cross head reciprocal on said frame, guides on said cross head in which said tubular member is mounted, said tubular member being movable back and forth with said die member, 65 cam means on the frame for moving said cross head back and forth, coöperating stops on the frame and on said tubular member for limiting the movement of its stripper pins in both directions, and means interposed between the cam and said cross head to reduce the speed of the opening movement of the movable die member and increase the force applied to effect the stripper 70 action.

42. In a die casting machine, a frame, a mold on the frame, a pot movable horizontally on the frame to position it against the mold, a horizontally extending support pin above the forward end of the pot from which 80 the pot is easily removable, a support lever pivoted to the frame below the rear end of the pot, the upper end of the lever straddling said pot, the upper end of the lever being notched, trunnions on the pot resting 85 in said notches, the pot being removable from the frame by raising the rear end of the pot to free the trunnions from the notches and moving the pot rearwardly to free it from said supporting pin.

In witness whereof, I hereunto subscribe my name this 21st day of May, A. D. 1918.

JOHN S. GULLBORG.
